UNITED STATES PATENT OFFICE.

WILHELM HOBOHM, OF BERLIN, GERMANY.

AUTOMATIC DOOR CLOSING AND LOCKING MECHANISM FOR VEHICLES.

1,095,634.

Specification of Letters Patent.

Patented May 5, 1914.

Application filed June 28, 1913. Serial No. 776,406.

To all whom it may concern:

Be it known that I, WILHELM HOBOHM, subject of the German Emperor, residing at 10 Taubenstrasse, Berlin, W., Germany, have invented a certain new and useful Improved Automatic Door Closing and Locking Mechanism for Vehicles, of which the following is a specification.

This invention relates to automatic door-closing and arresting mechanism for vehicles, and more particularly for passenger vehicles, motor-road vehicles and railway carriages of the type in which the door is automatically closed and in which mechanism is provided for arresting the door in a partly open position.

In apparatus of this type it has usually been possible to re-open the door by pressing against it from the inside. In other cases, the arresting mechanism prevented the door from being opened at any time beyond the position of arrest unless the arresting mechanism was put out of operation.

The object of the present invention is to provide a door-arresting mechanism which normally enables the door to be fully opened but operates on the closing of the door to arrest the door in a partly open position should the door bolt or latch not engage, so that the door cannot be re-opened until the arresting mechanism is manually released, as for example, by turning the door knob or handle to retract the door bolt or latch. By this means the door may be arrested in a partly open position, should the door not be sufficiently closed as to enable the bolt or latch to lock the door, while preventing accidental or unintentional re-opening of the door either on the starting or stopping of the vehicle or by a passenger leaning against the arrested door.

In order that the invention may be more clearly understood, reference is made to the accompanying drawings which show by way of example the preferred construction of my improved door-closing and arresting mechanism.

Figure 1 is a side view of the mechanism with the cover-plate removed. Fig. 2 is a transverse section through the mechanism

showing the same applied to a carriage door. Fig. 3 is a view corresponding to Fig. 1 showing the position of the parts when the door is fully open. Figs. 4, 5 and 6 are views corresponding to Fig. 2 showing the door in its closed, part open and fully open position respectively, the position of the parts in Fig. 4 corresponding to that shown in Figs. 1 and 2, and the position in Fig. 6 corresponding to that shown in Fig. 3. 60

1 designates any usual type of carriage latch having a sliding bolt 2 operated from a handle 40 by means of the tumbler 41 in the usual manner. Adjoining the latch 1 and secured to the door in any suitable manner is a casing 3 extending over the whole width of the door and within which is located the automatic door-closing mechanism. Fixed within the casing 3 is a block 4 carrying a spring pawl 5 which, when the door is in its closed position as illustrated in Figs. 1, 2 and 4, rests upon the front face of a slide block 7 having a notch 6 therein adapted to engage with the pawl 5 when the door is partly open. Slidably mounted upon 75 guides 31 within the casing 3 is a carriage or like member 8 connected to two springs 9 secured at their other ends at 10 to the casing 3, the carriage having rearwardly projecting spring detents 11 provided at 80 their rearward ends with inclined or cam faces 12 and 15, the inclined face 12 being adapted to rest against the correspondingly inclined end of the slide block 7 so as to rigidly connect the block 7 with the carriage 8. Secured to the block 7 is a cross-bar 14 connected to springs 13 connected at 85 their other ends to hooks 32 projecting from the carriage 8 so that the block 7 is furthermore connected to the carriage 8 through 90 the springs 13.

The block 7 is connected to one end of an articulated link chain 19 secured at its other end to the door frame 18. In lieu of a link chain 19 a steel band or rope or any other 95 suitable equivalent capable of withstanding a certain amount of longitudinal thrust may be employed. The chain 19 is guided through the opening of the door over a roller 20 mounted in the side of the door. Suit- 100

able guideways 21 serve to guide the block 7 in its movement on the opening of the door, the guideways 21 terminating at their rear ends in spring fingers 22 adapted, when 5 the block is in the position illustrated in Fig. 3, to grip the block 7 and thereby counter-balance the returning action of the springs 13, so that the door remains in its fully open position as illustrated in Fig. 6. 10 Slidably mounted in the block 4 and either connected to or bearing against the bolt 2 is a rod 23 passing through the carriage 8 and provided at its rear end with a plate 25 having an inclined rear edge 24 adapted to 15 move within a corresponding slot 26 in the forward end of the block 7. The rod 23 is provided with a collar 33 adapted to abut against the block 4 and to form an abutment for one end of a spring 23^a whose other 20 end bears against the carriage 8. In the drawing the rod 23 is shown adapted to abut against the bolt 2 and moves within the carriage 8 with sufficient friction as to be drawn to the rear therewith on the opening 25 of the door as shown in Fig. 3. This facilitates the true engagement of the plate 25 with the slot 26 in the block 7 on the closing of the door. It will be seen that when the plate 25 moves across the notch 6 in the block 30 7 the pawl 5 will be released or prevented from engagement with the notch 6.

The rear part of the door-closing mechanism is covered by means of a cover-plate 34 adapted to form an additional guide for the 35 block 7 and link chain 19, and secured at one end to the cover-plate 34 and at its other end to one end of a steel band 28 is a spring 27, the other end of the steel band being secured to the door frame 18. The purpose 40 of the steel band 28 is to protect the chain 19 when the door is open as in Fig. 6, and the spring 27 and band 28 may be protected by means of a casing 30.

The operation of the mechanism is as 45 follows: To open the door the bolt 2 is retracted in the usual manner by turning the handle 40, at the same time pushing the rod 23 toward the rear and causing the plate 25 to extend across the notch 50 6 in the block 7 and thus prevent the pawl 5 from engaging with the notch 6 on the opening of the door. As the door opens the chain 19 pulls the block 7 backwardly together with the carriage 8 against the action 55 of the springs 9 through the medium of the detents 11 connecting the block 7 with the carriage 8. The carriage 8 continues to move backwardly with the block 7 until the inclined faces 15 of the de- 60 tents 11 are forced outwardly and engage the inclined faces 16 of guideways 17, the outward movement of the detents 11 releasing the carriage 8 from the block 7. The carriage 8 then remains in the position illus-

trated in Fig. 3, the springs 9 being in tension. On the further outward movement of the door the block 7 is further retracted and the springs 13 are now stretched until the block 7 is grasped by the fingers 22, which prevent a return movement of the block 7. 65 The door is now in its fully open position as illustrated in Fig. 6.

On the closing of the door the chain 19, owing to its capability of withstanding a certain amount of longitudinal thrust, overcomes the action of the spring fingers 22 70 and commences to return the block 7, whereupon the springs 13 relax and, being somewhat weaker than the springs 9, commence to slowly close the door until the block 7 is 80 returned to such an extent that the inclined faces 12 of the detents 11 may again engage with the block 7 thereby releasing the carriage 8 and enabling the strong springs 9 to come into action to close the door. The 85 notch 6 of the block 7 thereby rides over the pawl 5 without engaging therewith. Should the door, however, not completely close under the action of the springs 9 as 90 may happen when an obstacle is caught between the door and its frame, the pawl 5 will enter the notch 6, as illustrated in Fig. 5, and prevent the door from being accidentally opened. It will be understood that, should the door so nearly close that the 95 notch 6 moves over the pawl 5 without engaging therewith, a slight pressure to reopen the door will cause the notch 6 to return until it engages with the pawl 5, so that the door will in any case be prevented 100 from unintentional opening.

When arrested in its partly open position the door may be readily released by turning the handle 40 and thus causing the bolt 2 to move the rod 23 and plate 25 to the 105 rear and disengage the pawl 5 from the notch 6 in the manner already described, whereupon the door may be fully opened.

I claim:—

1. In combination with the latch of a 110 hinged vehicle door, a catch, and releasing means operated by the latch retracting mechanism to temporarily release said catch and enable the door to be fully opened, said catch positively arresting the door in a 115 partly-open position on the closing of the door, should the latch not engage, until again released by reactuation of said releasing means.

2. In combination with the latch of a 120 hinged vehicle door, arresting mechanism comprising a fixed member and a member moved by the opening and closing of the door and adapted to engage said fixed member to arrest the door, and releasing means 125 operated by the latch retracting mechanism to temporarily disengage said members and enable the door to be fully opened, said

members engaging with each other to positively arrest the door in a partly-open position on the closing of the door, should the latch not engage, until again disengaged by 5 re-actuation of said releasing means.

3. The combination with a hinged vehicle door, mechanism for retaining the door in its partly closed position comprising a fixed member, a movable member coacting there- 10 with and mounted on the door, and a flexible connection from said movable member to the door frame capable of withstanding a certain amount of longitudinal thrust.

4. In combination with a hinged vehicle 15 door, a movable member on the door, a flexible connection between said member and the door frame, spring members adapted to be connected with said movable member when the door is closed and to be success- 20 sively tensioned by and released from said movable member on the opening of the door and to relax successively in reverse order to automatically close the door.

5. In combination with a hinged vehicle 25 door, a movable member on the door adapted to be moved by the opening and closing of the door, main springs adapted to effect the final closing of the door, auxiliary springs adapted to effect the initial closing of the 30 door and mechanism for coupling said main springs to said member when the door is closed, to cause said main springs to be tensioned when the door is opened, for uncoupling said main springs and holding them 35 in tensioned position and for tensioning said auxiliary springs from said member after the main springs have been tensioned.

6. In combination with a hinged vehicle 40 door, a movable member adapted to be moved by the opening and closing of the door, main springs adapted to effect the final closing of the door, auxiliary springs adapted to effect the initial closing of the door, detent mechanism connecting said main 45 springs to said member during the initial opening and final closing of the door, and for retaining said main springs in tensioned position, means cooperative with said detent mechanism for connecting said auxiliary 50 springs to said member during the final opening and initial closing of the door, and means for holding said auxiliary springs in tensioned position.

7. In combination with a hinged vehicle 55 door, a movable member on the door, a flexible connection between said member and the door frame, spring members adapted to be connected with said movable member when the door is closed and to be successively ten- 60 sioned by and released from said movable member on the opening of the door and to relax successively in reverse order to automatically close the door, and means for frictionally holding said movable member in re-

tracted position when the door is fully 65 opened.

8. In combination with a hinged vehicle door, a latch, a notched member movable on the door, a flexible connection between said member and the door frame, a fixed spring 70 pawl for engaging the notch in said member, a pawl disengaging element, and a rod actuated from said latch to move said element.

9. In combination with a hinged vehicle 75 door, a movable member on the door, a flexible connection between said member and the door frame, a sliding carriage, springs fixed at one end and connected at the other end to said carriage, detents carried by said carriage and adapted to engage said member, guides for retaining said detents in engagement with said member during the first part of its movement on the opening of the door, springs connected at one end to said carriage 80 and at the other end to said member, and a friction clamp for said member for holding it at the end of its movement on the opening of the door.

10. In combination with a hinged vehicle 90 door, a latch, a notched movable member on the door, a flexible connection between said member and the door frame, a fixed spring pawl for engaging the notch in said member, a pawl disengaging element, a rod actuated 95 from said latch to move said element, a sliding carriage, springs fixed at one end and connected at the other end to said carriage, detents carried by said carriage and adapted to engage said member, guides for retaining said detents in engagement with said member during the first part of its movement on the opening of the door, springs connected at one end to said carriage and at the other end to said member, and a friction 100 clamp for said member for holding it at the end of its movement on the opening of the door.

11. In combination with a hinged vehicle 110 door, a latch, a notched member movable on the door and having an open-ended slot in the end nearest the latch, a flexible connection between said member and the door frame, a fixed spring pawl for engaging the notch in said member, a slid- 115 able spring-returned rod normally bearing against the latch bolt, and a flat plate carried by said rod and having an inclined end face adapted to fit into the slot in said member.

12. In combination with a hinged vehicle 120 door, a movable member on the door, a flexible connection between said member and the door frame, a sliding carriage, springs fixed at one end and connected at the other end to said carriage, detents carried by said carriage and adapted to engage said member, guides for retaining said detents in engagement with said member during the first part

of its movement on the opening of the door, for releasing said carriage from said member at the end of the first part of the movement and for simultaneously retaining said carriage in its then position, springs connected at one end to said carriage and at the other end to said member, and a friction clamp for said member for holding it at the

end of its movement on the opening of the door.

In testimony whereof I have affixed my signature in presence of two witnesses.

WILHELM HOBOHM.
